(57) **CLAIM**

The ornamental design for a finish grade trim base, as shown and described.

DESCRIPTION

FIG. 1 is a rear perspective view of our finish grade trim base; FIG. 2 is a right side view thereof, the left side view being a mirror image thereof;

FIG. 3 is a front view thereof;

FIG. 4 is a rear view thereof;

FIG. 5 is a top view thereof; and,

FIG. 6 is a bottom view thereof.

In FIGS. 1 and 3 through 6 the finish grade trim base is cut to indicate indeterminate length.
